CLINCHING MACHINE

Harry Lev, Chicago, Ill.

Application February 27, 1947, Serial No. 731,344

9 Claims. (Cl. 1-4)

1

This invention relates to a machine adapted to assemble a metallic holder plate with the endless frame of a uniform cap. It is desirable that such a plate be affixed to the cap frame at the front to connect releasably with a strut which upstands to support the cap cover. In assembling the plate with the cap frame, it is important that the one be accurately positioned with respect to the other, that the holder plate be affixed securely to the cap frame, and that in carrying out this operation successively on many caps the assembly be uniform and dependable in every case.

For the purposes above indicated, I employ a simple form of machine adapted to impale the cap frame upon a plurality of pointed tines which are extended outwardly from the holder plate, and then, after impaling, clinch these tines, on the far side of the frame. This operation which takes place after the holder and cap frame have been correctly positioned one with respect to the other, may be followed by a ready and facile removal from the machine of the assembled cap frame and holder plate.

A suggestive embodiment of my invention is set forth in the accompanying drawing wherein:

Figure 1 is an outline view, in side elevation, of a foot-operated press whereon is mounted the parts of the present clinching machine;

Fig. 2 is a front elevation of a conventional uniform cap showing in dotted lines the position of the holder plate when affixed to the frame thereof;

Fig. 3 is a view in perspective of the holder plate designed for affixation to the cap frame;

Fig. 4 which is a view in perspective shows the principal parts of the clinching machine;

Fig. 5 is a longitudinal vertical section through the machine in its entirety;

Fig. 6 is a fragmentary section showing the cap frame with holder plate affixed thereto as the assembly appears at the conclusion of the clinching operation; and

Fig. 7 is a sectional detail view, taken on line 1-1 of Fig. 4.

The special problem for which the present machine has been developed is the clinching of certain tines *t* struck out from a bowed holder plate *P*, the purpose being to thereby secure the plate to the frame *f* (usually of fabric and fiber

2

plies) of a uniform cap *C*. Such a holder plate, when affixed to the cap frame at the front, is adapted to detachably receive between itself and certain offset bands *b* the lower end of an upstanding strut by which the cap cover is supported in a raised position.

The present machine which performs such a tine-clinching operation comprises a base plate 10 fixedly mounting at the rear a T-block having a forwardly extending abutment wall 11. Straddling this wall is a movable die block 15 having at its base outwardly extending flanges 16 which are cooperatively engaged by guide bars 17 affixed to the base plate. In some such way as this I provide means for assuring that movements of the die block upon the base plate will be in a straight line forwardly and rearwardly toward and from the T-block.

The die block is slotted forwardly from its rear face to provide a channel 20 having its base face 21 inclined rearwardly (see Fig. 5) for cooperative engagement from a similarly inclined face 22 at the lower end of a ram 23 which is carried at the lower end of a rod 24 which is mounted for vertical reciprocation in the head 25 of a press having a conventional treadle-operated bell crank 26. With each down stroke of the ram, the die block is advanced forwardly against the tension of springs 28, one extending along each side of the die block to connect at its front with a cross pin 29 projecting laterally therefrom and at its rear with a pin 30 which is anchored to the T-block. The forward face of the abutment wall 11 may be provided with an inclined undercut at 31 to accommodate the inclined rear face 21 of the die block, thereby to increase its movement range, and for a like reason there may be an opening 32 in the base plate to accommodate the bottom end of the ram when in its lowermost position.

The acting front face 36 of the die block is here shown as inwardly bowed or concave in a transverse direction to conform to the acting outwardly bowed face 37 of an aligned coacting anvil block 38 which is disposed opposite thereto and slightly spaced therefrom. The anvil block 38 is provided at its front with a laterally extended head 39 having near each end an opening through which is fitted a rearwardly extending threaded stud bolt 40. As by means of stud

bolts 41 (see Fig. 5) the anvil block 38 is secured fixedly to the base plate 10.

The anvil block lies between two companion blocks 45, each in the form of a quadrant, and both surmounted by a common top plate 46 of semi-circular form. As by means of stud bolts 47 the top plate is fixedly connected to the two quadrant blocks, thereby joining them into a single unit which I shall refer to collectively as a positioning form. Within each quadrant block is a bore 48 extending from its forward face parallel with the anvil block 38 and opposite one of the stud bolts 40 so as to be supported thereby is a compression spring 49 adapted to exert a thrust force against the inner end of the bore 48 whereby the positioning form is normally urged in a direction of the die block 15 and arrested by an arcuate stop ring 50 that is anchored to the base plate.

The top plate 46 which desirably is beveled at 51 along its curved periphery is adapted also to overlie the head 39 of the anvil block 38. This plate may be marked with an arrow 53 at the midpoint of its periphery which is directly opposite the center of the die block 15. Desirably also a slot 54 is extended radially of the top plate at its center to accommodate a stud 55 which is screw threaded into the anvil block, the head 56 of this stud being disposed upon the top face of the plate. By this means the anvil block and top plate are locked against separation, but without interfering with movement of the positioning form toward and from the die block 15.

In operation, a holder plate P is fitted to the acting face 37 of the anvil block 38 wherein are provided cross channels 60 for reception of the bars b which are offset from the plate. Normally the acting face of the anvil block is recessed with respect to the adjacent faces of the quadrant blocks 45, so that the holder plate is accommodated within this recess. When the holder plate is operatively positioned, the tines t will be extended outwardly toward the die block in whose acting face 36 are formed cam pockets 61, one opposite each tine. The endless frame f of a cap C is then fitted over the top plate and down around the positioning form so as to lie in part within the narrow space between the die and anvil blocks. In practice, a small locating mark (not shown) will be carried by the welt of the cap frame at exactly its front center point. The cap frame may then be accurately centered by positioning this mark opposite the center arrow 53. With the holder and frame thus arranged, the tines t stand opposite the frame and die block ready to be driven through the frame and be clinched upon the far side thereof. This operation takes place in consequence of a forced descent of the ram which drives the die block 15 forwardly to impale the cap frame f upon the tines t whose tips, upon engaging the cam pockets 61, are then laterally turned and clinched thereby. In this operation the positioning form is free to recede relative to the die block 15, counter to tension of the springs 49, as required for complete impaling of the tines t through the cap frame f and clinching of the tine tips upon the far side thereof.

It will be observed that by the straddling arrangement which permits the anvil block to guide the positioning form in its reciprocations, the acting face of the anvil block is normally recessed so as to accommodate therein the holder plate when it is to be operated upon. When so

positioned, the outset bands b of the holder plate may lie within the channels 60, as best shown in Fig. 6, permitting the body of the plate to rest against the face of the anvil block. This is important because it safeguards the outset bands against pressure during the ensuing clinching operation, whereby to prevent any distortion or displacement thereof. Also the springs 49, in urging the positioning form in a direction toward

10 the die block 15 to a position beyond the acting face of the anvil block, act to shift the cap frame, together with its assembled holder plate, away from the anvil block, thereby freeing the cap frame at the conclusion of each operation for ready removal from off the positioning form. This is advantageous because I thereby provide, in effect, an ejector which facilitates removal of the work at the conclusion of each operation.

The entire mechanism herein disclosed is exceedingly simple and sturdy, and will withstand hard service over a prolonged period. There is no uncertainty about the position of the cap plate relative to the holder plate which is to be affixed thereto, since there is a visual guide for assisting in the placement of the cap frame and a positive accommodating recess for positioning of the holder plate. For this reason, as well as because the operation of impaling and clinching the tines will be performed with certainty and uniformity with each operation of the mechanism, the successive assembly of cap frames and head plates may proceed with dispatch and with a minimum of effort.

I claim:

35 1. Means for assembling with a cap frame a holder plate having a plurality of outstanding tines, comprising a stationary anvil block, a reciprocable positioning form straddling the anvil block for guidance thereby, spring means urging 40 the positioning form ahead of the acting face of the anvil block whereby the position of the latter is recessed to accommodate therein the holder plate with its tines outwardly extended, a movable die block having its acting face formed with cam pockets disposed oppositely of the tines when the holder plate is positioned operatively upon the anvil block, and normally spaced therefrom a distance sufficient to accommodate therebetween the cap frame when fitted over the positioning form, and means for reciprocating the die block toward and from the anvil block to initially engage the cap frame for impaling the same upon the holder tines and then to engage the protruding tines in the cam pockets whereby to laterally deflect and crimp the tips thereof upon the cap frame.

2. Means for assembling with a cap frame a holder plate having a plurality of outstanding tines, comprising a stationary anvil block, a reciprocable positioning form including a block on each side of the anvil block and a top plate connecting the two side blocks in unitary relation for reciprocable movement lengthwise of the anvil block, spring means urging the positioning form ahead of the acting face of the anvil block whereby the position of the latter is recessed to accommodate therein the holder plate with its tines outwardly extended, a movable die block having its acting face formed with cam pockets disposed oppositely of the tines when the holder plate is positioned operatively upon the anvil block, and normally spaced therefrom a distance sufficient to accommodate therebetween the cap frame when fitted over the positioning form, and means for reciprocating the die block toward

and from the anvil block to initially engage the cap frame for impaling the same upon the holder tines and then to engage the protruding tines in the cam pockets whereby to laterally deflect and crimp the tips thereof upon the cap frame.

3. Means for assembling with a cap frame a holder plate having a plurality of outstanding tines, comprising a stationary anvil block, a positioning form straddling the anvil for guidance thereby, compression springs carried by the anvil block and extending in parallelism toward the positioning form to exert thereagainst a thrust force acting to move the positioning form ahead of the acting face of the anvil block, whereby the position of the latter is recessed to accommodate therein the holder plate with its tines outwardly extended, a movable die block having its acting face formed with cam pockets disposed oppositely of the tines when the holder plate is positioned operatively upon the anvil block, and normally spaced therefrom a distance sufficient to accommodate therebetween the cap frame when fitted over the positioning form, and means for reciprocating the die block toward and from the anvil block to initially engage the cap frame for impaling the same upon the holder tines and then to engage the protruding tines in the cam pockets whereby to laterally deflect and crimp the tips thereof upon the cap frame.

4. Means for assembling with a cap frame a holder plate having a plurality of outstanding tines, comprising an anvil block, a positioning form including a block on each side of the anvil block and a top plate interconnecting the two side blocks in unitary relation, means providing a normally inseparable sliding connection between the anvil block and the positioning form whereby one, when moved relative to the other, is guided thereby, spring means urging the positioning form ahead of the acting face of the anvil block whereby the position of the latter is recessed to accommodate therein the holder plate with its tines outwardly extended, a movable die block having its acting face formed with cam pockets disposed oppositely of the tines when the holder plate is positioned operatively upon the anvil block, and normally spaced therefrom a distance sufficient to accommodate therebetween the cap frame when fitted over the positioning form, and means for reciprocating the die block toward and from the anvil block to initially engage the cap frame for impaling the same upon the holder tines and then to engage the protruding tines in the cam pockets whereby to laterally deflect and crimp the tips thereof upon the cap frame.

5. Means for assembling with a cap frame a holder plate having a plurality of outstanding tines, comprising a stationary anvil block, a reciprocable positioning form straddling the anvil block for guidance thereby, spring means urging the positioning form ahead of the acting face of the anvil block whereby the position of the latter is recessed to accommodate therein the holder plate with its tines outwardly extended, means providing a stop to limit movement of the positioning form in one direction, a movable die block having its acting face formed with cam pockets disposed oppositely of the tines when the holder plate is positioned operatively upon the anvil block, and normally spaced therefrom a distance sufficient to accommodate therebetween the cap frame when fitted over the positioning form, and means for reciprocating the die block toward and from the anvil block to initially engage the cap frame for impaling the same upon the holder

tines and then to engage the protruding tines in the cam pockets whereby to laterally deflect and crimp the tips thereof upon the cap frame.

6. Means for assembling with a cap frame a holder plate having a band outset from one face thereof and a plurality of tines outstanding from its opposite face, comprising a stationary anvil block, a reciprocable positioning form straddling the anvil block for guidance thereby, spring means urging the positioning form ahead of the acting face of the anvil block whereby the position of the latter is recessed to accommodate therein the holder plate with its tines outwardly extended, there being a channel in the acting face of the anvil block to accommodate the band outset from the holder plate, a movable die block having its acting face formed with cam pockets disposed oppositely of the tines when the holder plate is positioned operatively upon the anvil block, and normally spaced therefrom a distance sufficient to accommodate therebetween the cap frame when fitted over the positioning form, and means for reciprocating the die block toward and from the anvil block to initially engage the cap frame for impaling the same upon the holder tines and then to engage the protruding tines in the cam pockets whereby to laterally deflect and crimp the tips thereof upon the cap frame.

7. Means for assembling with a cap frame a holder plate having a plurality of outstanding tines, comprising an anvil block, a positioning form extending upon opposite sides of the anvil block, spring means for producing relative reciprocable movement between the anvil block and the positioning form whereby the position of the acting face of the anvil block is normally recessed to accommodate therein the holder plate with its tines outwardly extended, a movable die block having an acting face disposed oppositely of the tines when the holder plate is positioned operatively upon the anvil block and normally spaced therefrom a distance sufficient to accommodate therebetween the cap frame when fitted over the positioning form, and means for producing a relative back and forth movement between the die block and the anvil block to engage opposite faces of the cap frame for impaling the same upon the holder tines.

8. Means for assembling with a cap frame a holder plate having a plurality of outstanding tines, comprising a die block and a coacting anvil block one movable toward and from the other which is stationary and each having a complementary acting face opposite the other and normally spaced therefrom, a positioning form extending upon opposite sides of the anvil block, spring means for producing relative reciprocable movement between the positioning form and the anvil block whereby the acting face of the latter is normally recessed to accommodate therein the holder plate with its tines outwardly extended, the spacing between the acting faces of the two blocks, when one is moved away from the other, being sufficient to accommodate therebetween the cap frame when fitted over the positioning form, and means for causing the movable block to successively advance toward and recede from the stationary block to engage opposite faces of the cap frame whereby to impale the same upon the holder tines.

9. Means for assembling with a cap frame a holder plate having a plurality of outstanding tines, comprising a die block and a coacting anvil block one movable toward and from the other and each having a complementary acting face

opposite the other and normally spaced therefrom, a positioning form extending upon opposite sides of the anvil block, spring means for producing relative movement between the positioning form and the anvil block whereby the acting face of the latter is normally recessed to accommodate therein the holder plate with its tines outwardly extended, the spacing between the acting faces of the two blocks, when one is moved away from the other, being sufficient to accommodate therebetween the cap frame when fitted over the positioning form, and means for moving one block toward and from the other to cause a successive closing and opening of the space between their

5 acting faces whereby the cap frame intermediately thereof is impaled upon the holder tines.
